SCRIBER

Fred J. Zimowske, Mio, Mich.

Application October 30, 1937, Serial No. 171,997

8 Claims. (Cl. 33—41)

This invention relates to a scribe and more particularly to an instrument of this type used for marking logs which are to have portions interfitted with each other when building a log cabin or similar structure.

When building a log cabin, it is necessary that end portions of the logs have interfitting engagement with each other at corners of the building so that they will be interlocked and the logs forming intersecting walls prevented from moving out of their proper relation to each other. It is also necessary to provide an interlocking connection between the rafters and the plate log along upper edges of the walls so that the rafters will be braced and prevented from slipping out of proper engagement with the plate log.

Therefore, one object of the invention is to provide a scribe, by means of which overlapping portions of logs may be marked and recesses cut which will accurately receive portions of intersecting logs. It will thus be seen that the logs may be so cut that a recess formed therein will accurately conform to the outline of a portion of a log to be received therein and close fitting interlocking engagement established between the intersecting logs.

Another object of the invention is to so form the scribe that an arm carrying a pencil or equivalent marker may be adjusted to dispose it at a predetermined height above the lower end of a fixed leg of the scribe according to the diameter of the log which is to be cut and thus a recess of the proper depth assured.

It is another object of the invention to provide the scribe with a head carrying a level and thus permit the operator to at all times maintain the scribe in its proper angular position for marking a log.

Another object of the invention is to so mount the head carrying the level that it may be angularly adjusted with its neck pivoted to the body portion of the scribe and disposed either parallel to the side face of the blade or at right angles thereto in a position either beyond the upper end of the blade or substantially parallel to a side edge of the blade.

It is another object of the invention to provide a scribe wherein the level is carried by a mounting disk pivoted to the adjustable head in such a manner that it may be turned about an axis to an adjusted position.

The invention is illustrated in the accompanying drawings, wherein

Figure 1 is a view in elevation showing the scribe in use,

Figure 2 is a view in elevation looking from the right of Figure 1.

Figure 3 is an enlarged side elevation of the scribe,

Figure 4 is a view taken along the line 4—4 of Figure 3,

Figure 5 is a sectional view taken along the line 5—5 of Figure 3, and

Figure 6 is a view looking down upon the level and the disk carrying the same.

This improved scribe has a body in the form of a blade 1 which is cut from sheet metal of sufficient thickness to impart rigidity to the blade. The lower portion of the blade extends diagonally and forms a leg 2 which is tapered towards its lower or free end and at its lower end is beveled, as shown at 3, to provide a marginal edge or surface extending at right angles to the longitudinal axis of the blade. An upper corner portion of the blade at the opposite side thereof from the leg is formed arcuate, as shown at 4, and intermediate the length of this arcuate edge the blade is formed with a recess 5 which extends radially of the arcuate edge but terminates in spaced relation to an opening formed through the blade 25 to receive a bolt 6. The arcuate edge or corner portion 4 is concentric to the opening through which the bolt extends, as clearly shown in Figure 3. There has also been provided a slot 7 which extends longitudinally of the blade adjacent to but spaced from the side edge of the blade at the opposite sides thereof from the arcuate corner portion, and attention is called to the fact that the lower end of this slot terminates adjacent the upper end of the leg 2.

The scribe includes as one of its elements a marker 8 which may be a pencil or a scoring device formed of hard steel. This marker is carried by a tubular arm 9 formed with a longitudinally extending slot 10 in its under portion and with a shorter slot 11 leading from the rear end of its upper portion. Wings 12 extend downwardly at a rearward incline from the lower portion of the tubular arm at opposite sides of the lower slot 10 for engagement with opposite side faces of the blade 1 where they are secured by a bolt 13 which passes through the slot 7 and carries a wing nut 14. It will thus be seen that the arm may be shifted longitudinally of the blade and also turned about the bolt 13 from a position in which the arm and marker extend longitudinally of the blade to a position in which they extend transversely from the same. When the tubular arm is disposed transversely of the blade, a portion of the blade fits into the upper

slot 11, and when the tube is disposed longitudinally of the blade, a portion of the blade engages in the slot 10. Therefore, the marker may be disposed close against the blade longitudinally thereof when not in use where it will be out of the way. This position of the marker close to the blade also prevents likelihood of the point of the pencil being accidentally broken or the pointed end of a metal marker being accidentally bent or snapped off.

At the upper end of the blade there is disposed a bracket 15 formed of sheet metal, the blank from which the bracket is formed being molded intermediate its length to provide leaves 16 connected by leaves 17 through which a pivot pin passes. The leaves straddle the upper portion of the blade and adjacent their inner or lower ends are formed with aligned openings which register with the openings through which the bolt 6 passes. Therefore, when the bolt is passed through the registering openings of the wings 16 and the blade, the bracket will be pivotally connected with the upper portion of the blade and may be swung from a position in which it extends longitudinally of the blade, as shown in full lines in Figure 3, to a position transversely of the blade, as indicated by dotted lines in this figure. The fact that the blade is formed with the arcuate upper corner portions permits the bracket to have this swinging movement. Recesses 19 which are in opposed relation to each other are formed in the upper portion of the bracket and are adapted to register with the recess or slot 5 when the bracket is turned about the bolt 6 to a diagonally extending position midway between the dotted line position and the full line position of Figure 3.

The head or disk 20 is formed of stiff sheet metal and carries a bearing bracket 21 which is secured against its under face by rivets 22. This bearing bracket is formed with depending hinge ears 23 and between the hinge ears is located a block 24 which loosely passes through the opposed slot 19 of the bearing bracket 15. The lower portion of this block is of semi-circular outline, as shown in Figures 4 and 5, and at opposite sides of this semi-circular lower portion 24' there have been formed slots 25 and 26, another slot 27 being formed intermediate the width of the semi-circular lower portion. All of the slots 25, 26 and 27 extend radially of the semi-circular lower portion which is concentric to the pin or rod 18, and when the head is turned to a position in which it extends diagonally of the blade with the slot 19 of the bearing bracket in registry with the slot 5 of the blade, the head may be turned about the pin 18 into position to dispose a selected one of the slots 25, 26 or 27 in registry with the registering slots of the blade and bearing bracket. The head may then be moved to a position disposing it beyond the upper end of the blade or at a side thereof and since a portion of the blade will be passed through the selected slot of the block 24 the head will be secured in a set position and extend either transversely of the blade, as shown in Figures 3, 4 and 5, or in a plane parallel to a selected side face of the blade according to which position will be most convenient to the person using the scribe.

The scribe should be maintained in a predetermined angular position when in use, such as the perpendicular position shown in Figures 1 and 2, and in order to do so, there has been provided a level 28 consisting of a bubble glass 29 which extends diametrically across a mounting disk 30

and has its ends seated in pockets 31 carried by the disk. This disk rests upon the central portion of a mounting disk 32 where it is secured by rivets 33. Marginal portions of the mounting disk extend downwardly at an incline to dispose the peripheral edge of the mounting disk in close contacting engagement with the circular plate 20 and degree markings are provided upon the downwardly extending portion of the mounting disk, as shown in Figure 6, so that, when the mounting disk is turned about the pivot pin 34 which holds it in operative engagement with the plate 20, the extent to which the mounting disk has been turned relative to the lug or extension 20' of the disk 20 can be ascertained. It will thus be seen that the mounting disk constitutes a dial which is concentric to the plate 30 and that the level 28 extends diametrically of the dial. The level not only serves its purpose as a level but also constitutes a finger hold, by means of which the dial or mounting disk can be turned about the pivot 34 to an adjusted position when using the device.

When this device is in use, it may be used for marking logs at corners of a building or for marking other logs, such as roofing rafters or the logs forming a partition, which should have its ends interlocked with logs of a wall. In Figures 1 and 2, the scribe has been shown in use for marking intersecting logs at the corner of a building. Referring to these figures, it will be seen that the log 35 has already been interlocked with the log 36 and the log 37 is to be recessed so that it can have interlocking engagement with the log 35. In order to do so, the log 37 must be formed with a recess to receive the upper portion of the log 35, and this recess should be so formed that it will snugly receive the upper portion of the log 35 and thus cause the two logs to fit properly in interlocking engagement with each other and prevent movement of the logs relative to each other. In order that a recess may be properly cut in the log 37, this log is set in place across the log 35 and the scribe then disposed in an upright position upon the upper portion of the log 35. The arm 9 carrying the marker 8 is swung to a horizontal position and shifted upwardly to such a height that it is approximately halfway the thickness of the log 37 and the winged nut 14 then tightened so that the marker will be firmly secured in the set position. The plate 20 is preferably disposed over the upper end of the plate 1 when the scribe is in use, as shown in Figures 1 and 2, but it will be understood that it may be swung downwardly to the position indicated by dotted lines in Figure 3 or it may be turned to a position towards the right or left in Figure 4 according to which position will make it most convenient for the operator to see the dial 32 and the level 28. The dial will be turned to a position in which the bubble in the glass 29 will be centrally located and this will make it easy to maintain the scribe in the upright position. The scribe is then moved across the log 35 while still held in the upright position and, as it moves across the log 35 and downwardly along the same, the marker 8 will form a pencil mark or scratch upon the log 37 which will substantially exactly follow the outline of the log 35. After the scribe has been moved from the upper portion of the log 35 to a position at one side thereof as indicated by dotted lines in Figure 2, it will be returned to the original position shown in full lines in this figure and moved toward the other side of the log 35. Therefore, the log 75

37 will be marked in conformity to the outline of the projecting upper portion of the log 35. The scribe will then be transverse to the other side of the log 37 and the log 37 again marked. Therefore, if the log 35 tapers somewhat instead of being of the same diameter at opposite sides of the log 37, the two sides of the log 37 will be properly marked and, when the wood is cut from the log 37 in accordance with the markings thereon, the log 37 will be formed with a recess which will snugly receive the projecting upper portion of the log 35 and a close interlocking fit will be established between the logs 35 and 37. Other intersecting logs of a building will be similarly marked, such as by placing rafters or roofing logs in their proper position and then marking their end portions to form recesses to receive portions of a ridge pole and the plate log of the walls of a building. If it is desired to provide spacings for the inner surfaces of the walls of a building, this can be easily done by marking marginal portions of wall boards which are to have contacting engagement with the logs of the walls or partitions of the building.

Having thus described the invention, what is claimed as new is:

1. A scribe comprising a blade formed with a longitudinally extending slot in spaced parallel relation to one edge thereof, a leg extending from the lower end of the blade and projecting from the said side edge of the blade at a downward incline, a tubular carrier having its inner end portion straddling the blade and formed with wings engaging opposite side faces of the blade, a fastener extending through the wings and through the slot of the blade and mounting the carrier for pivotal adjustment about the fastener and longitudinal adjustment relative to the blade, a marker removably carried by said tubular carrier and projecting from the outer end thereof, and means carried by said blade for determining the angular position of the blade relative to a vertical position.

2. A scribe comprising a blade, a leg extending from the lower end of said blade at a downward incline from one side edge of the blade, a marker adjustable longitudinally of the blade and mounted for pivotal movement into and out of position to extend transversely of the blade from the said side edge thereof, and means carried by the upper portion of the blade for determining the angular position of the blade relative to a vertical position.

3. A scribe comprising a blade, a marker carried by said blade and adjustable longitudinally thereof, a bearing bracket pivoted to the upper portion of the blade and movable from a position longitudinally of the blade to a position transversely thereof, and means carried by said bearing bracket for determining the angular position of the blade relative to a vertical position when the marker is in use.

4. A scribe comprising a blade, a marker carried by said blade and adjustable relative thereto, a bearing bracket pivoted to the upper portion of the blade and movable from a position longitudinally of the blade to a position transversely thereof, a block pivotally carried by said bearing bracket, said block being formed with slots to receive the upper portion of the blade and the blade and bearing bracket being formed with slots adapted to register and permit turning of the block to adjusted positions, a mounting carried by said block, and means carried by said mounting for ascertaining the angular position

of the blade relative to a vertical position when the marker is in use.

5. A scribe comprising a blade, a marker carried by the blade and adjustable relative thereto, a bearing bracket straddling the upper portion of the blade and having wings engaging opposite side faces of the blade, a fastener passing through the blade and the leaves of said bearing bracket to pivotally mount the bracket for movement from a position longitudinally of the blade to a position transversely thereof, said blade being formed with a slot leading from an upper corner portion and the bearing bracket having its leaves formed with slots for registering with the slot of the blade, a block pivotally carried by said bearing bracket and having a portion extending through the slots of the leaves, the block being of semi-circular outline and formed with slots spaced from each other circumferentially thereof, said block being movable through the slots of the blade and bearing bracket when the slots thereof are in registry to move a selected slot of the block into position to receive the upper portion of the blade and hold the block in an adjusted position when the bearing bracket is moved to one of the said positions of adjustment, a disk carried by said block at the outer end thereof, a dial pivoted to the disk, the disk having marginal portions projecting beyond the dial and formed with an indicator and the dial having gage markings about its periphery, and a level carried by said dial and extending diametrically of the dial and disk.

6. A scribe comprising a body adapted to be supported in an upright position, a marker carried by said body and projecting from one side thereof, a bearing carried by the upper end of said body and movable from a position in which it projects above the upper end of the body to a position in which it projects from a side of the body, and means for determining the angular position of the body relative to a vertical position carried by said bearing and pivotally mounted for movement transversely of the bearing and body.

7. A scribe comprising a body adapted to be supported in an upright position, a marker carried by said body and adjustable longitudinally thereof, a bearing pivoted to said body for adjustment from a position in which it extends above the upper end of the body to a position in which it projects from a side of the body, a mounting carried by said bearing and pivotally mounted for movement transversely of the bearing and body from a position transversely of the body to a position substantially parallel thereto, and means for determining the angular position of said body relative to a vertical position carried by said mounting and mounted for turning movement to adjusted positions.

8. A scribe comprising a body adapted to be supported in an upright position, a marker carried by said body and adjustable longitudinally thereof, a bearing bracket pivoted to said body for adjustment from a position in which it projects above the upper end of the body to a position in which it projects from a side of the body, a mounting pivoted to said bracket for movement from a position transversely of the body to a position substantially parallel thereto, said mounting having a member adapted to pass through the bracket and the body and hold the bracket in an adjusted position, and means for determining the angular position of said body relative to a vertical position carried by said mounting.
